A. PETZOLD.

RUG.

No. 16,178.

Patented July 21, 1885

UNITED STATES PATENT OFFICE

ADOLPH PETZOLD, OF PHILADELPHIA, PENNSYLVANIA.

DESIGN FOR A RUG.

SPECIFICATION forming part of Design No. 16,178, dated July 21, 1885.

Application filed April 11, 1885. Term of patent 3½ years.

To all whom it may concern:

Be it known that I, ADOLPH PETZOLD, a citizen of the United States, and a resident of Philadelphia, Pennsylvania, have invented and produced a new and original Design for a Rug, of which the following is a specification, reference being had to the accompanying photographic illustration, to which reference is made.

- 10 The accompanying illustration represents one half of my rug, the design or pattern of which is shown as cut in half across the narrow part, the other half being a duplicate of what is shown.
- 15 The design consists of an outer broad border, A, surrounding an inner narrow strip or inner border, B, and a middle rectangular panel, C. The outer border, A, is ornamented with leaves D D, resembling oak-leaves, and scrolled or 20 partially-curved leaves E E, with large flowers F F. The narrow border B contains at inter-

vals the diamond-shaped figures G G, each ornamented with a cross, as shown. Intermediate between these figures G G is the zigzagged ornamentation H. The central panel contains 25 the large scrolls and leaves I I, flowers or figures J J, and a large central open scalloped flower or figure, K.

While my design may be changed in small details without destroying or changing the effect aimed at, its leading features are the outer broad border, A, the narrow border B, and the central rectangular panel, C, all ornamented substantially as shown in the accompanying 30 illustration.

What I claim is—

The design for a rug, substantially as shown and described.

ADOLPH PETZOLD.
